UNITED STATES PATENT OFFICE.

JACOB DYM, OF PITTSBURGH, PENNSYLVANIA, ASSIGNOR TO PORCELIER MANUFACTURING COMPANY, OF PITTSBURGH, PENNSYLVANIA, A CORPORATION OF PENNSYLVANIA.

DESIGN FOR A LIGHTING BRACKET.

Application filed January 20, 1928. Serial No. 24,945. Term of patent 14 years.

To all whom it may concern:

Be it known that I, JACOB DYM, a citizen of the United States, residing at Pittsburgh, in the county of Allegheny and the State of Pennsylvania, have invented a certain new, original, and ornamental Design for Lighting Brackets, of which the following is a specification, reference being had to the accompanying drawings, forming a part hereof.

The single figure is a view in perspective

of my new design for lighting brackets made of porcelain or like material.

I claim:

The ornamental design for a lighting bracket as shown.

In testimony whereof, I have hereunto subscribed my name this 14th day of January, 1928.

JACOB DYM.
